UNITED STATES PATENT OFFICE

90,443

DESIGN FOR A COMBINATION HALL TREE

Walter Reed Johnson, Suffern, N. Y.

Application April 25, 1933. Serial No. 47,897

Term of patent 3½ years

To all whom it may concern:

Be it known that I, WALTER REED JOHNSON, a citizen of the United States, residing at the village of Suffern, in the county of Rockland and State of New York, have invented a new, original, and ornamental Design for a Combination Hall Tree, of which the following is a specification, reference being had to the accompanying drawing, forming part thereof,

The figure is a perspective view of the article showing my new design.

I claim:

The ornamental design for a combination hall tree, as shown.

WALTER REED JOHNSON.
